(57) **CLAIM**

The ornamental design for automobile tire, as shown and
described.

DESCRIPTION

FIG. 1 is a front view of an automobile tire, showing the new
design, the rear view, top plan view and bottom plan view
appearing the same as the front view;

FIG. 2 is a right side view of the tire, a left side view
appearing the same as the right side view;

FIG. 3 is a fragmentary front view, showing in enlargement
the portion of lines 3—3 in FIG. 1;

FIG. 4 is a cross-sectional view taken along line 4—4 in
FIG. 3; and,

FIG. 5 is a cross-sectional view taken along line 5—5 in
FIG. 3.
